UNITED STATES PATENT OFFICE.

WILLIAM RULISON, OF RAHWAY, NEW JERSEY, ASSIGNOR TO MERCK & CO., OF NEW YORK, N. Y., A CORPORATION OF NEW YORK.

SHAKER RECEPTACLE.

Application filed February 21, 1924. Serial No. 694,256.

To all whom it may concern:

Be it known that I, WILLIAM RULISON, a citizen of the United States of America, residing at Rahway, in the county of Union and State of New Jersey, have invented certain new and useful Improvements in Shaker Receptacles, of which the following is a specification.

This invention relates to certain new and useful improvements in shaker receptacles and particularly to the type of receptacle adapted to contain fluent powdered material having a valved top wall construction to control the discharge of the fluent material from the receptacle.

The primary object of this invention is to provide an improved type of an apertured plate having a spring member associated therewith and an apertured cover for the receptacle with the apertures of the plate and receptacle cover brought into registration upon sliding the plate and embodying co-operating guide means carried by the sliding plate and the spring for insuring true reciprocal movement of the sliding plate.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a fragmentary side elevational view of a shaker receptacle constructed in accordance with the present invention.

Figure 2 is a top plan view showing the perforations in the receptacle cover and showing by dotted lines the perforations in the sliding plate with the finger piece for operating the sliding plate extending through a slotted opening in the cover.

Figure 3 is a vertical sectional view, taken on line III—III of Fig. 2 showing the loop spring formed integral with the sliding plate and depending therefrom.

Figure 4 is a horizontal sectional view taken through the cover of the receptacle showing the guide arms on the sliding plate enclosing the free end of the spring to cooperate therewith and form a guide for the sliding plate.

Figure 5 is a developed plan view of the

blank from which the sliding plate and spring are formed, and

Figure 6 is a perspective view of the sliding plate and spring.

The shaker receptacle 1 may be of any preferred design and constructed of the desired material to contain a fluent powdered or gritty material 2 to be discharged from one end of the can or receptacle by shaking the latter.

The upper end of the can is provided with a top wall 3 set therein as shown in Fig. 3 and anchored at its peripheral edge to the upper edge of the receptacle. A relatively large opening is formed centrally of the top wall 3 and is surrounded by an upstanding bead 4.

A cover 5 closes the upper end of the receptacle and is spaced from the top wall 3 and bead 4 and has a depending peripheral flange 6 enclosing the side walls of the receptacle. The cover 5 is provided with a plurality of perforations 7 disposed centrally thereof as shown in Fig. 2 and is also provided adjacent one edge thereof with a slot 8.

A valve member is associated with the perforated cover 5 and is interposed between the cover and top wall bead 4, the same being in the form of a slidably mounted plate 9 having perforations 10 formed therein that are normally out of registration with the openings in the cover and are adapted to be moved into registration therewith. One side of the plate 9 carries a neck extension 11 that slidably projects through the slot 8 in the cover 5 with the outer end of the neck bent upwardly as at 12 to form a finger piece for manually sliding the plate. The blank from which the valve device is formed is shown in detail in Fig. 5, the side thereof opposite the neck extension 11 carrying a spring arm 13 formed integral therewith and cut into the body of the plate as at 14 to provide spaced side guide arms 15.

The spring 13 is bent into loop formation as shown in Figs. 3 and 6 to provide spaced spring legs 16 and 17, the free end of the spring leg 17 being angularly bent outwardly as at 18 and disposed in the same plane as the plate 9 and located between the guide arms 15.

The plate 9 being slidably mounted upon the top wall bead 4, the terminal end 18 of the spring leg 17 overlies the bead 4 as

shown in Fig. 3 with the side edges of the upper end of the spring leg 17 engaging the inner face of the bead 4 as shown in Fig. 4. The loop spring has a normal tendency to separate the legs thereof and move the plate 9 in a direction away from the spring leg 17 to displace the openings 7 and 10 in the cover 5 and plate 9 respectively out of registration. By pressing 10 upon the finger piece 12, the plate 9 is shifted against the tension of the loop spring to move the perforations into registration and permit the contents of the receptacle to be discharged therethrough. During this 15 movement, as will be evident from an inspection of Figs. 4 and 6, the plate 9 is guided in its movements by the guide arms 15 enclosing the bent end 18 of the spring leg 17 insuring true lineal reciprocating 20 movements for the plate 9 and proper registration of the perforations 7 and 10. One of the principal features of the present invention is to provide the cooperating 25 guide means for the sliding plate formed as component parts of the plate and spring with the spring forming an integral part of the plate. The spring end 18 and the plate 9 constantly assume their proper relative positions in view of the mounting 30 thereof within the upper end of the receptacle between the top wall 3 and cover 5.

It is believed that the construction and operation of the device will be fully understood from the above description and it is intended that various changes in details of 35 construction are contemplated as will fall within the scope of the invention as herein-after claimed.

What is claimed as new is:—

40 1. In a shaker receptacle, a receptacle having a perforated cover, a manually 45 slideable plate having perforations adapted to register with the perforations in the receptacle cover, a loop-spring struck-out 48 from the plate and depending therefrom with the free end of the spring lying in the same plane as the plate, and guide arms on 50 said plate inclosing and cooperating with the free end of the spring to constitute a guide for the plate.

2. In a shaker receptacle, a receptacle having a perforated cover, a manually 55 slideable plate having perforations adapted to register with the perforations in the re-

ceptacle cover, a loop-spring struck-out 65 from the plate and depending therefrom with the free end of the spring bent outwardly at an angle and lying in the same plane as the plate, and guide arms on said plate inclosing and cooperating with the 70 free end of the spring to constitute a guide for the plate.

3. The combination with a shaker receptacle having a perforated cover, of a 65 perforated sliding valve plate struck from a sheet of metal, said plate having a finger piece for sliding the same, a loop-spring carried by one edge of the plate and extending into the body of the plate to provide spaced arms, and the free end of the spring 70 disposed between said arms and cooperating therewith to form a guide for the plate.

4. In a shaker receptacle, a receptacle, a top wall having an opening therein, an apertured cover for the receptacle spaced 75 from the top wall and having a slotted opening therein, a sliding apertured plate overlying the top opening and contacting the cover, a spring formed integral with the plate and depending therefrom with the 80 free end of the spring extending downwardly through the top wall opening and bent inwardly thereof, guide arms on said plate disposed at opposite sides of the bent end of the spring, and a finger piece for 85 sliding the plate extending outwardly through the slotted opening in the cover.

5. In a shaker receptacle, a receptacle, a top wall having an opening therein, an upstanding bead surrounding the opening, 90 an apertured cover for the receptacle spaced from the top wall and having a slotted opening therein, a sliding apertured plate overlying the top opening, supported on the bead and contacting the cover, a spring 95 formed integral with the plate and depending therefrom with the free end of the spring extending downwardly through the top wall opening and bent inwardly thereof, guide arms on said plate disposed at opposite sides of the bent end of the spring and a finger piece for sliding the plate extending outwardly through the slotted opening in the cover.

In testimony whereof I affix my signature.

WILLIAM RULISON.
